UNITED STATES PATENT OFFICE

114,379

DESIGN FOR A TEXTILE FABRIC OR SIMILAR ARTICLE

Marie A. Szach, Astoria, N. Y., assignor to Cheney Brothers, New York, N. Y., a corporation of Connecticut

Application February 15, 1939, Serial No. 83,007

Term of patent 3½ years

To all whom it may concern:

Be it known that I, Marie A. Szach, a citizen of the United States, residing at Astoria, in the county of Queens and State of New York, have invented a new, original, and ornamental Design for a Textile Fabric or Similar Article, of which the following is a specification, reference being had to the accompanying drawing, forming a part thereof.

The figure is a face view of a textile fabric or similar article showing my new design.

I claim:

The ornamental design for a textile fabric or similar article as shown.

MARIE A. SZACH.
